Application February 6, 1952, Serial No. 270,245

18 Claims. (Cl. 183—42)

1

The present invention relates to compressor systems for gaseous fluids such as air and the like embodying a moisture separator and liquid trap, and, more particularly, to improvements in systems and apparatus of the type disclosed in my copending application for United States Letters Patent, Serial Number 746,830, filed May 8, 1947, now Patent Number 2,585,045, dated February 12, 1952.

The present invention is primarily concerned with compressor systems for aircraft which systems are capable of functioning at below zero atmospheric temperatures such as encountered at high altitudes. In such systems air from the atmosphere is compressed, and the moisture in the compressed air is separated therefrom and is collected in liquid form in a trap from which the liquid is expelled periodically under the control of the compressor or apparatus associated with the compressor system.

In a practical installation of such a system on aircraft, the compressor and the moisture separator and/or trap may be located a considerable distance apart, thus requiring a substantial length of connecting tubing or conduit in which moisture may condense and collect when the compressor is idle. This condensed moisture will freeze at low temperatures and obstruct the tubing or conduit to thereby prevent flow of compressed air therethrough upon subsequent operation of the compressor.

Accordingly, an object of the present invention is to provide an improved compressor system which overcomes the foregoing difficulty.

Another object is to provide such a compressor system wherein the trap and/or moisture separator and the connecting tubing are purged by dry gas at intervals to expel moisture and/or liquid therefrom.

Another object is to provide such a compressor system wherein the purging is under the control of the operation of the compressor.

Another object is to provide an improved moisture separator and trap which is particularly adapted for low temperature operation.

A further object is to provide such a moisture separator and trap which is simple and practical in construction, reliable in operation, and is readily manufactured and assembled in an economical manner.

Other and further objects of the invention will be obvious upon an understanding of the illustrative embodiment about to be described, or will be indicated in the appended claims, and various advantages not referred to herein will occur to

one skilled in the art upon employment of the invention in practice.

In accordance with the present invention, the foregoing objects are generally accomplished by providing a compressor system which comprises a compressor having an outlet; a storage receptacle to which compressed fluid from the compressor is to be supplied; a moisture separator and liquid trap having a compressed fluid inlet, an outlet connected to the receptacle, a drainage outlet and a valve for the drainage outlet including pressure operable means for normally closing the valve; conduit means connecting the compressor outlet with the separator inlet and the pressure operable means; a valve having an inlet connected with the compressor outlet and having a venting outlet; and means under the control of the compressor operable to effect closing and opening of the last mentioned valve.

20 A preferred embodiment of the invention has been chosen for purposes of illustration and description and is shown in the accompanying drawings, forming a part of the specification, wherein:

25 Fig. 1 is a schematic view, partly in section, illustrating a compressor system including a moisture separator and trap and a control valve with the operating parts of the trap and the valve in the positions they assume when the compressor is idle.

30 Fig. 2 is a schematic view, partly in section, illustrating a portion of the system shown in Fig. 1 with the operating parts of the trap and the valve in the positions they assume when the compressor is in normal operation.

35 Fig. 3 is a detailed longitudinal sectional view of a moisture separator and trap embodying the present invention.

40 Fig. 4 is a sectional view taken along the line 4—4 on Fig. 3.

Fig. 5 is a sectional view taken along the line 5—5 on Fig. 3.

45 Referring to the drawings in detail and more particularly to Figs. 1 and 2 thereof there is shown a system for compressing and storing air at a pressure of about 3000 pounds per square inch. This system generally comprises a compressor 10 having an outlet 11; a moisture separator and liquid trap 12 having a chamber 13, an inlet 14, an outlet 15, a drainage outlet 16 and a valve 17 for controlling the drainage outlet including pressure operable means such as a piston 18 and a piston chamber 20 for normally closing the valve; a valve 21 having an inlet 22 connected with the compressor outlet 11 and having a venting outlet

24; means under the control of the compressor operable to effect closing and opening of the valve 21, about to be described; conduit means including a tube 25 of substantial length connected at one end with the compressor outlet 11 and valve inlet 22, and including a passageway 26 extending to the piston chamber 20 and a passageway 27 extending to the interior of the moisture separating chamber 13 or inlet 14 provided with a spring loaded check valve 28, which passageways are in communication with the other end of the tube 25 and each other; and a storage receptacle 29 connected to the separator outlet 15 by a conduit 30 having a check valve 31 therein.

The compressor 10 is shown schematically as comprising a cylinder 35, a piston 36 and a rod 37 connecting the piston to a crankshaft 39, but it will be understood that the compressor may be of any suitable design of either single or multiple stage type. In a practical installation, a compressor such as shown in my prior Patent No. 2,562,954 may be utilized wherein the final cylinder of the stage of compression is provided with the outlet 11.

The valve 21 is also shown somewhat schematically and essentially comprises a body 40 formed at one end with a valve seat 41 communicating with the valve inlet 22, the venting outlet 24 at its side, and a cylinder or piston chamber 42 at its other end having an inlet 44; a valve member 45 for the seat 41; a piston 46 in the cylinder 42 carrying the valve members; and a spring 47 acting on the piston to maintain the valve member off its seat.

The means under the control of the compressor for effecting closing and opening of the valve, in addition to the piston 46 and the spring 47, include other elements responsive to the operation of the compressor. These elements act to move the piston upwardly to cause the valve to engage its seat and shut off communication between the valve inlet 22 and its venting outlet 24 while the compressor is in normal operation, and act to permit the spring to move the piston downwardly to unseat the valve and establish communication between the valve inlet 22 and its venting outlet 24 when the compressor is idle or is operating at substantially below its normal speed.

Such elements may be associated with the lubricating system of the compressor, which, for example, generally comprises a path through which oil is circulated, herein shown as a conduit 50 in communication with the cylinder inlet 44, and an oil pump 51 including a cylinder 52, a piston 54 and a rod 55 connecting the piston to the crankshaft 39 of the compressor.

In Fig. 1, the valve elements of the system just described are illustrated in the positions they assume prior to operation of the compressor 10. When the compressor is idle, the oil pump 51 also is idle and no oil is circulated through the conduit 50. Consequently, no pressure is exerted on the piston 46 by the oil and the spring 47 holds the piston in a position whereby the valve member 45 is off its seat 41 to establish communication between the valve inlet 22 and the venting outlet 24. Also, when the compressor is idle, no compressed air is flowing from the compressor outlet 11 to the moisture separator and liquid trap 12, whereby the check valve 28 shuts off communication between the passageway 27 and the chamber inlet 14. The position of the drainage control valve 17 is immaterial, but, for example, as shown, may be off its seat to establish com-

munication between the chamber 13 and the drainage outlet 16. Compressed air, if any, in the receptacle 29 is prevented from flowing through the outlet 15 and into the chamber 13 by the check valve 31.

When the compressor 10 is put into operation, the oil in the lubricating system is pumped and the pressure thereof acts on the piston 46 to seat the valve member 45 and thereby shut off communication between the inlet 22 and the venting outlet 24 (Fig. 2). Compressed air from the compressor enters the tube 25, the passageway 26 and the chamber 20 to raise the valve 17 carried by the piston 19 and effect closing of the drainage outlet 16 (Fig. 2). As the pressure in the tube 25 and the passageway 27 builds up, the valve 28 is unseated (Fig. 2) to admit air into the chamber 13 wherein separation of moisture therefrom is effected and the separated liquid is collected. The compressed air, from which moisture has been removed, leaves the chamber by way of the outlet 15, passes through the valve 31 and enters the storage receptacle 29.

When the compressor stops or is operated at an abnormally low rate, the pressure of the oil in the lubricating system drops to a low value and the spring 47 acts on the piston 46 to move the valve member 45 off its seat 41 and thereby establish communication between the valve inlet 22 and venting outlet 24 (Fig. 1). As this occurs, the tube 25, the passageways 26 and 27 and the piston chamber 20 are vented, whereby the valve 28 closes and the valve 17 opens (Fig. 1). The pressure of the air in the chamber 13, upon opening of the valve 17, is effective to blow collected liquid through the drainage outlet 16 and thereby empty the trap. Prior to closing of the valve 28, dry air in the chamber is rapidly released through the tube 25 to purge the same of liquid which may have been condensed or collected therein to expel such liquid through the valve 21 to its venting outlet 24. After this has been accomplished, the tube contains moisture free dry air which prevents condensation and freezing of liquid in the tube 25 while the compressor is idle and the system is subjected to below freezing temperatures.

It will be appreciated that, upon unclosing of the venting outlet 24, air in the conduit connecting the compressor outlet 11 and the valve inlet 22 is relieved through the outlet 24. Also, the check valve 31 closes when the air compressor stops to prevent return flow of the air in the storage receptacle 29 and to thereby limit the quantity of air utilized in blowing out the trap and purging the tube 25.

In a practical installation of a system in accordance with the present invention, the valves 17, 21 and 28 are constructed and arranged to cooperate at predetermined pressures. When the compressor starts, the pressure of the oil of the lubricating system upon exceeding 20 pounds per square inch closes the valve 21, and the pressure of the compressed air upon exceeding 150 pounds per square inch closes the valve 17. As the pressure of the compressed air builds up to 800 pounds per square inch, the valve 28 opens and air passes through the separator to remove moisture and trap the same in liquid state. Air pressure continues to build up to 3000 pounds per square inch, and the compressed dry air is collected in the storage receptacle.

When the compressor stops or is operated at a speed whereby the oil pressure drops below 20 pounds per square inch, the valve 21 opens, and the pressure of the air in the moisture separator

and trap falls to 400 pounds per square inch in about two seconds, whereupon the valve 28 closes. As the pressure of the air in the tube 25, the passageways 26 and 27, and the chamber 20 continues to drop to 150 pounds per square inch, the drainage valve 17 is opened by air at 400 pounds per square inch in the separator chamber 13, and this air blows out the trap. The air in the separator and the tube 25 continues to vent therefrom until the same is reduced to atmospheric pressure.

Referring now to Figs. 3 to 5, there is shown in detail a moisture separator and liquid trap 12, such as schematically illustrated in and described in connection with Figs. 1 and 2, wherein like elements are designated by like reference numerals. This separator and trap structure generally comprises a tubular body part 60 providing the chamber 13, a head 61 attached to the upper end of the part 60, and a base 62 attached to the lower end of the part 60.

The base 62, as shown in Figs. 3 and 5, is a generally rectangular metallic block formed with a circular boss 64 at the top thereof which extends into the lower end of the body part 60 and which has an annular groove 65 for a gasket 66 providing a seal between the body part and the base. The boss also has a conical liquid collecting recess 67 which is formed with a central drainage opening 69 at the bottom thereof having a valve seat 68.

The base 62 is further formed with an enlarged vertical bore 70 extending from the opening 69 to the bottom, a horizontally extending bore 71 (Fig. 3) which intersects the bore 70 adjacent the lower end thereof having one end in communication with the tube 25, a vertical bore 72 in communication with the other end of the bore 71, a horizontally extending bore 74 communicating with the bore 70 adjacent the opening 69 and serving as the drainage outlet, a horizontally extending bore 75 for an electrical heater 76, and a recess 77 (Fig. 5) for housing a thermostatically controlled switch 79, the purpose of which will become apparent hereinafter.

A plug 80 is threadedly secured in the bore 70, and is formed with a central bore serving as the chamber 20 for the piston 19 carrying the valve member 17 which is positioned to engage the seat 68.

Diametrically opposite openings 81, at the lower end of the piston chamber bore 70 and in alignment with the bore 71 (Fig. 3) establish communication between the piston chamber 13 and the bore 71 and establish communication between the opposite ends of the bore 71, whereby compressed air entering the bore 71 from the tube 25 will cause the piston 19 to raise the valve member against its seat 68 and will flow to the bore 72.

The head 61, as shown in Figs. 3 and 4, is a generally rectangular metallic block formed with a circular boss 84 at the bottom thereof which extends into the upper end of the body part 60 and which has an annular groove 85 for a gasket 86 providing a seal between the body part and the head. The boss also has a central vertical bore 87 in which a depending tube 88 is mounted to serve as the inlet for the chamber 13, and has an annular groove 89 surrounding the lower end of the bore 87 in which a depending tube 90, slightly shorter than the tube 88, is mounted to serve as the outlet for the chamber, as about to be described.

The head 61 is further formed with a horizontally extending bore 91, a restricted bore 92 connecting the bores 87 and 91 and tangentially 75

disposed with respect to the bore 87 to serve as a nozzle for imparting swirling motion to compressed air entering the tube 88 whereby mechanical separation of moisture from the air is effected, a vertical bore 94 in communication with the bore 91 and in alignment with the bore 72 of the base, a horizontally extending outlet bore 95 to which the conduit 30 is connected, a vertical bore section 96 (Fig. 4) connecting the bore 95 and the groove 89, and a horizontal bore 97 adjacent the bore 87 for mounting an electrical heater 98.

The bore 91 has an open end in which a plug 100 is threadedly secured, and has a closed end opposite the open end. The plug 100 is formed with a valve seat 101 at its inner end against which the check valve member 28 is held by a spring 102 in the closed end of the bore 91, and has a duct 103 extending therethrough for establishing communication between the bore 94 and the valve seat opening.

In order to connect the base bore 72 and the head bore 94 whereby compressed air is conducted from the tube 25 to the chamber inlet 14, 25 a tube 104 has its ends extending into the bores 72 and 94, respectively, and suitable means are provided for forming a seal between the ends of the tube and the base and head, respectively. Such means preferably include a packing such as 30 a small O-ring 105 facing the end of the tube 104, and a short tube section 106 extending through the O-ring and into the tube 104 and a restricted portion of the bores 72 and 94, respectively. This arrangement provides a tight seal 35 as well as a floating connection between the bores 72 and 94 whereby the length of the tube need not be maintained within extremely accurate dimensions.

As previously indicated, the head 61 and base 40 62 are attached to the body part or tube 60. This is accomplished in a convenient manner by forming the head and base with aligned apertures 107, and mounting bolts 109 in these apertures which have heads 110 engaging the underside of the base and have their upper ends threaded into the apertures 107 of the head.

The separator and trap structure as described so far, preferably is encased in a heat insulating housing. This housing may comprise a tubular shell 111 having a mounting bracket 112 attached thereto, and an upper cover 114 and a lower cover 115 engaging the respective ends of the shell. In order to connect the shell and covers to the encased separator and trap structure, screws 116 extend through the upper cover 114 and are threaded into the head 61 to hold this cover against the upper end of the shell, and screws 117 extend through the lower cover 115 and are threaded into the base 62 to hold this cover against the lower end of the shell.

The purpose of the heaters 76 and 98 is to prevent moisture or liquid from freezing in the bores of the head and base, particularly in the nozzle 92 and the drainage opening 69, but by constructing the head and base of metal, heat will be conducted throughout the head and base to prevent freeze-ups in other bores or passages thereof. These heaters are of the resistance type, and are connected in an electrical circuit under the control of the switch 79 which in turn is electrically connected to a connector 119 mounted on the lower cover 115 for plugging in a source of electrical energy. The heater thermostat or switch 79 may be constructed and arranged to close at about 45° F. and to open at about 60° F.

whereby the temperature of the head and base is always well above the freezing point of water.

The separator and trap structure illustrated in Figs. 3 to 5 operates in the same manner as the separator and trap 12 of the system illustrated schematically in Figs. 1 and 2.

From the foregoing description, it will be seen that the present invention provides an improved compressor system of the class described which embodies an improved moisture separator and liquid trap particularly adapted for use on aircraft and other installations where low temperatures are encountered. The system is practical and reliable, and the separator functions therein to expel trapped liquids at intervals in response to the action of the compressor and to purge connecting conduits between the separator and the compressor outlet to prevent freeze-ups while the compressor is idle.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. In a compressor system of the class described, the combination of a compressor having an outlet; a storage receptacle to which compressed fluid from said compressor is to be supplied; a moisture separator having an inlet, an outlet connected to said receptacle, a drainage outlet and a valve for said drainage outlet including pressure operable means for normally closing said valve; conduit means connecting said compressor outlet with said separator inlet and said pressure operable means; a valve having an inlet connected with said compressor outlet and having a venting outlet; and means under the control of said compressor operable to effect closing and opening of said last mentioned valve.

2. In a compressor system of the class described, the combination of a compressor having an outlet; a storage receptacle to which compressed fluid from said compressor is to be supplied; a moisture separator having an inlet, an outlet connected to said receptacle, a drainage outlet and a valve for said drainage outlet including pressure operable means for normally closing said valve; conduit means connecting said compressor outlet with said separator inlet and said pressure operable means; a valve having an inlet connected with said compressor outlet, a venting outlet and a valve member for controlling the flow of fluid from said valve inlet to said venting outlet; and means under the control of said compressor for operating said valve member.

3. In a compressor system of the class described, the combination of a compressor having an outlet; a lubricating system for said compressor wherein the lubricant is pressurized; a storage receptacle to which compressed fluid from said compressor is to be supplied; a moisture separator having an inlet, an outlet connected to said receptacle, a drainage outlet and a valve for said drainage outlet including pressure operable means for normally closing said valve; conduit means connecting said compressor outlet with said separator inlet and said pressure operable means; a valve having an inlet connected with said compressor outlet, a venting outlet and a valve member for controlling the flow of fluid from said valve inlet to said venting outlet; and means including a piston chamber and a piston

in said chamber under the control of the pressure of the lubricant of said compressor lubricating system for operating said valve member.

4. In a compressor system of the class described, the combination of a compressor having an outlet; a storage receptacle to which compressed fluid from said compressor is to be supplied; a moisture separator having an inlet, an outlet connected to said receptacle, a drainage outlet, a valve for said drainage outlet including pressure operable means for normally closing said valve, and a check valve for permitting the flow of fluid from said separator inlet towards said separator outlet; conduit means connecting said compressor outlet with said separator inlet and said pressure operable means; a valve having an inlet connected with said compressor outlet and having a venting outlet; and means under the control of said compressor operable to effect closing and opening of said last mentioned valve.

5. In a compressor system of the class described, the combination of a compressor having an outlet; a storage receptacle to which compressed fluid from said compressor is to be supplied; a moisture separator having an inlet, an outlet connected to said receptacle, a drainage outlet, a valve for said drainage outlet including pressure operable means for normally closing said valve, conduit means connecting said separator inlet and said pressure operable means, and a check valve for permitting the flow of fluid from said separator inlet towards said separator outlet; a valve having an inlet connected with said compressor outlet and having a venting outlet; a conduit connecting said separator inlet and said inlet of said last mentioned valve; and means under the control of said compressor operable to effect closing and opening of said last mentioned valve.

6. In a compressor system of the class described, the combination of a compressor having an outlet; a lubricating system for said compressor wherein the lubricant is pressurized; a storage receptacle to which compressed fluid from said compressor is to be supplied; a moisture separator including a chamber having an inlet and having an outlet connected to said receptacle and having a drainage outlet, a valve for said drainage outlet, pressure operable means for normally closing said valve, conduit means connecting said compressor outlet and said pressure operable means, passageway means connecting said chamber inlet and said conduit means, and a check valve in said passageway means for permitting the flow of fluid at a predetermined pressure into said chamber; a valve having an inlet connected to said conduit means, a venting outlet and a valve member for controlling the flow of fluid from said valve inlet to said venting outlet; and means including a piston chamber and a piston in said chamber under the control of the pressure of the lubricant of said compressor lubricating system for operating said valve member.

7. A moisture separator of the class described comprising a head, a base, a tubular body between said head and said base providing a separating chamber, said base having a passageway extending therethrough provided with an inlet for compressed gas from which moisture is to be removed and an outlet and having a drainage conduit extending from said separating chamber to the exterior thereof including a valve seat and a valve chamber, a valve member in said valve chamber, pressure operable means in said base including

an opening in communication with said passageway for causing said valve member to engage said seat, said head having a passageway therein provided with an inlet and an outlet in communication with said separating chamber and having an outlet conduit extending from said separating chamber to the exterior thereof, and means for establishing fluid flow communication between said outlet of said base passageway and said inlet of said head passageway.

8. A separator according to claim 7, wherein check valve means are provided in said head passageway for controlling the flow of fluid therethrough.

9. A separator according to claim 7, wherein said head and said base have heating means therein.

10. A separator according to claim 9, wherein said heating means are of the electrical resistance type connected in a circuit including a thermostatically controlled switch.

11. A moisture separator of the class described comprising a head, a base, a tubular body between said head and said base providing a separating chamber, said base having a passageway extending therethrough provided with an inlet for compressed gas from which moisture is to be removed and an upwardly facing outlet opening and pressure operable drainage means for said chamber, said head having a passageway provided with a downwardly facing inlet opening in alignment with said outlet opening and an outlet in communication with said chamber and having a second passageway extending from said chamber to the exterior, a connecting tube having its ends in communication with said outlet opening and said inlet opening respectively, means for providing a seal between said tube and said openings, means for providing a seal between the ends of said tubular body and said head and said base respectively, and means for securing said head and said base together to secure said tubular body and said connecting tube between said head and said base.

12. A moisture separator of the class described comprising a head, a base, a tubular body between said head and said base providing a separating chamber, said head having an inlet conduit and an outlet conduit in communication with said chamber, said base having a passageway extending therethrough provided with an inlet for compressed gas from which moisture is to be removed and an outlet in fluid flow communication with said inlet conduit, said base having a central bore extending through said passageway and formed with a reduced upper end communicating with said chamber and surrounded by a valve seat and having a bore extending outwardly from said central bore, a member in said central bore forming a closure for the lower end of said central bore and formed with a piston chamber at its upper end and having aperture means for establishing communication between said passageway and said piston chamber, a piston in said piston chamber, and valve means supported by said piston for engaging said valve seat.

13. A moisture separator according to claim 12, wherein said base is formed with a bore adjacent the upper region of said central bore and an electrical heating unit is disposed in said last mentioned bore.

14. A moisture separator of the class described comprising a head, a base, a tubular body between said head and said base providing a separating chamber, said head having an inlet conduit including an inlet end for compressed gas from which moisture is to be removed, a downwardly extending outlet end bore and a nozzle section between said inlet end and said outlet end bore adapted to impart swirling motion to said gas entering said bore, a tube depending from said outlet end bore terminating in said chamber for accumulating said moisture from said gas, and a second tube surrounding said first tube and spaced therefrom, said head having an outlet conduit including an end in communication with said chamber at a point intermediate said tubes.

15. A moisture separator according to claim 14, wherein a check valve is positioned in said inlet conduit between said inlet end and said nozzle section, said check valve being constructed and arranged to unseat in response to a predetermined pressure of the gas entering said inlet end.

16. A moisture separator according to claim 14, wherein said head is formed with a bore adjacent said outlet end bore and an electrical heating unit is disposed in said last mentioned bore.

17. A moisture separator comprising a head, a base, a tubular body between said head and said base providing a separating chamber, said head having a compressed gas inlet conduit formed with a centrally located vertical section in communication with said chamber and having an outlet conduit having a horizontal section, said base having a drainage outlet conduit including a centrally located vertical section in communication with said chamber and a horizontal section, valve means for controlling said drainage outlet, a horizontally disposed electrical heating unit in said head adjacent said vertical and said horizontal conduit sections, and a horizontally disposed electrical heating unit in said base adjacent said vertical and horizontal sections of said drainage outlet conduit.

18. A moisture separator according to claim 17, wherein said heating units are connected in a circuit including a thermostatically controlled switch.

ALBERTUS E. SCHMIDLIN.
